UNITED STATES PATENT OFFICE.

WILLIAM F. KIESEL, JR., OF ALTOONA, PENNSYLVANIA.

MOLDING.

No. 866,479.

Specification of Letters Patent.

Patented Sept. 17, 1907.

Application fil. 1 November 24, 1906. Serial No. 344,855.

To all whom it may concern:

Be it known that I, WILLIAM F. KIESEL, Jr., a citizen of the United States, residing at Altoona, in the county of Blair and State of Pennsylvania, have invented certain new and useful Improvements in Moldings, of which the following is a specification.

This invention relates to improvements in metal moldings to be used in metal interior work for producing ornamental effects in cornices, panels and the like, 10 and relates more particularly to moldings applicable to the inside finish of the higher grade of steel passenger cars; my object being to provide moldings which may be bolted in place and the bolt heads concealed so as to present a smooth and artistic appearance, thereby enabling me to employ an all-steel construction for the inside finish. I attain my object by constructing the moldings as illustrated in the accompanying drawings, in which—

Figure 1 represents a side elevation of a portion of a 20 car interior with inside sheathing or surface plates and partitions of metal, having applied thereto cornice, corner and panel moldings embodying my invention; Fig. 2, a horizontal section of Fig. 1 where said figure is broken off at the bottom; Fig. 3, a transverse section of 25 the parts constituting the cornice molding on an enlarged scale; Fig. 4, a similar section through the panel molding; Fig. 5, a perspective view illustrating three modifications of the panel molding; and Fig. 6, a perspective view of a modified form of corner molding.

Like numerals designate like parts in the several views.

In carrying out my invention the interior of a car or other structure will be finished with metal sheathing or surface plates attached to the frame-work in any approved manner. These sheathing or surface plates 1 will preferably be fastened together along their meeting edges by means of flanges 2 formed thereon upon the reverse side, said flanges being riveted together and the seam covered and concealed by means of a V-shaped 5 piece of metal 3 riveted in between the flanges, this joint between plates being described and claimed in a companion application. Where there are partitions, the cross-plates forming the partitions will be secured to the side plates and the rivet joints concealed by corner moldings produced in conformity with my invention. In Figs. 1 and 2 a transverse partition plate is shown at 4 riveted to the side plate 1 by means of angles 10, the rivet heads on the inside being concealed by means of light metal plates 6 sprung in between the 45 limbs of the angles, said limbs near their outer edges being provided with longitudinal projections 7 formed either by grooving the angles or by slightly bending up the edges of the plates of which the angles are made.

To finish off the top of the side walls or partitions,

where desirable (as at the line of the spring of the 55 arch of the lower deck ceiling in car interiors), I provide a cornice molding 8 formed from comparatively thin plates of steel or other metal pressed or drawn into suitable ornamental shapes, said cornice moldings being provided with longitudinal channels to receive the 60 rivets by which they are bolted to the sheathing and partition plates. This channel, after the cornice molding is in place, will be filled by a suitable insert to conceal the rivets and give to the cornice a smooth and artistic finish. As shown in Figs. 1 and 3, this insert 65 consists of a metal plate having flaring side flanges which are sprung into the channel formed in the molding, said channel being of dove-tail section, to retain the metal insert in place. This insert may be of the same metal as the molding, or of a different metal to 70 produce any desired color effect. The molding at each side of the channel will be completed by bending the plate outwardly therefrom with any desired curves and angles and finally back to points in alignment with the back of the channel, so that the edges of the molding at 75 top and bottom will rest against the sheathing plates. These top and bottom edges of the molding may extend slightly beyond the line of the back of the channel in order that, when the molding is riveted in place, said edges may bear tightly against the surface of the sheathing plates. The spring action of the insert also assists in pressing these top and bottom edges against the plates.

To break up the plainness of the metal panels thus produced, or to frame in window and door openings cut 80 through the panels, I provide moldings 10 which are riveted to the sheathing plates or to frame members where they lie back of the sheathing plates, said moldings being fitted together by miter joints where they inclose a space on, or an opening through, the plates. 90 These moldings 10 are also formed from steel or other metal plates having longitudinal channels, the plates at each side of the channels being bent outwardly and then backwardly to bring their outer edges in alignment with the back of the channel. In Figs. 1, 2 and 4 95 these panel moldings are shown with dove-tail channels, and the insert plates 11 are similar to the inserts 9, being sprung into the channels after the moldings have been bolted into place. These panel moldings, at each side of the channels, may be pressed or drawn into any 100 desirable shapes.

Instead of using the metal inserts, I may fill the channels with plastic material, such as asbestoslith or monolith, rolled or pressed in after the moldings have been fastened in place and dressed off to a smooth surface. 105 Plastic inserts are shown at 13 and 16 in the moldings illustrated in Fig. 5. In the center of the figure I have shown the same molding 10, as described above, the

channel being filled with an insert of plastic material, at each side of which is a strip of metal or colored asbestos fiber to produce an inlaid effect, the molding 10, plastic insert 13 and strips 14 being finished in different colors to relieve the plainness of the molding and to produce any desired colored effect. The molding at the left hand side of Fig. 5 consists of a channel with the sides bent inward and provided with reentrant flanges between which the insert plate 11 is sprung. At the right hand side of the figure, a molding is shown in which the envelop 15 is provided with bent-in sides and reentrant flanges, the channel so formed being completely filled with an insert of plastic material 16.

In place of the plain angle moldings for corners described in connection with Figs. 1 and 2, I may employ angles 17 (see Fig. 6), having their outward edges bent to form a longitudinal channel with outward return bends having curves and angles to produce a more ornamental effect, the insert in this case being preferably of plastic material, as shown at 18.

As thus described, moldings of various ornamental designs may be produced from bent metal plates and fastened wherever required to finish off cornices, corners, panels, window and door casings, and the like, the

means by which they are fastened in place being entirely concealed, with artistic and pleasing effect.

What I claim as my invention and desire to secure by Letters-Patent is:

1. A molding provided with a dove-tail channel having bolt holes at the back thereof, in combination with an insert comprising a plate of channel form having flaring sides adapted to be sprung into said channel after the bolts are in place.

2. A molding comprising a metal plate bent to form a longitudinal channel, the plate at each side of the channel being bent outwardly and then backwardly, the backward bends terminating at points in alignment with the back of the channel, said channel back being provided with one or more bolt holes, and an insert adapted to be applied to the channel to conceal the bolts.

3. The combination, with a metal surface plate, of metal moldings bolted thereto to produce cornice, panel and like effects, said moldings, where the bolts are applied, being provided with recesses, and inserts within said recesses fastened thereon after the bolts are in place, said inserts concealing the bolts and surfacing the recesses in conformity with the lines of the moldings.

In testimony whereof I have affixed my signature, in presence of two witnesses.

WILLIAM F. KIESEL, JR.
